UNITED STATES PATENT OFFICE

2,468,466

REFRIGERATION COIL FOR CIRCULATED AIR

Arnold A. D. Shanis, Philadelphia, Pa.

Application July 1, 1946, Serial No. 680,651

2 Claims. (Cl. 62—102)

1

My invention relates to refrigeration and relates particularly to a refrigeration coil.

Heretofore, refrigeration coils have been used in refrigerators whereby evaporated liquids absorb heat and condensing gases absorb cold. When a liquid in a refrigeration machine is forced to evaporate to be a gas, the refrigerant absorbs heat from the surrounding meats and vegetables and all food products liquid or solid thereby lowering their temperatures. Most of the domestic refrigerating machines employ this principle of alternating liquids and gases.

In the prior art, the cooling coil used had a plurality of fins thereon, which fins were made of metal to provide a better transfer of heat from the space outside of the coil to the chemical within the coil. Heat was transferred to the chemical from the fins by means of conduction and the area of heat transfer was increased by virtue of the fins.

The cost of placing fins upon the coil is relatively high and it is for the purpose of reducing this cost and increasing efficiency that my invention is directed.

Another object of my invention is to provide a coil for a refrigerator which coil may be used as a freezer plate.

Another object of my invention is to provide a refrigeration coil wherein all of the liquid contained therein will be vaporized.

Another object of my invention is to provide a length of copper tubing wherein it is constructed to serve as a self-holding spring as well as a cooling coil.

Another object of my invention is to provide a coil for a refrigerator wherein the frost collecting upon the coil is kept at a minimum amount.

Other objects of my invention are to provide an improved device of the character described, which is sturdy in construction, and which is highly efficient in operation.

With the above and related objects in view, my invention consists in the details of construction and combination of parts, as will be more fully understood from the following description, when read in conjunction with the accompanying drawing in which:

Fig. 1 is a fragmentary view of a refrigerator embodying a refrigeration coil of my invention.

Fig. 2 is a side view of the refrigeration coil of my invention.

Fig. 3 is a front view of the refrigeration coil of my invention.

Fig. 4 is a side view of the refrigeration coil.

2

Fig. 5 is a top view of the refrigeration coil and blower.

Fig. 6 is a front view of the refrigeration coil and blower.

5 Fig. 7 is a bottom view of the refrigeration coil and blower.

Fig. 8 is an end view of the refrigeration coil and blower.

Referring now in detail to the drawing, I show 10 a refrigerator designated as A, having a centrifugal blower with an impeller, generally designated as B. The purpose of the impeller B is to draw warm air from one portion of the refrigerator and direct it over a coil, generally designated 15 as C.

The coil C comprises a length of copper tubing wound into the form of a helix with its spaced convolutions each of elliptical shape, that is, the coil generally has a configuration of an ellipse but 20 it advances for each turn. It is very important that each convolution is arranged to tilt at an angle of approximately 45° to the horizontal plane for the following purposes:

(a) Of serving as a tension spring against the 25 outer shield or shell for the purpose of holding itself within the shell and

(b) The coil contacts the metallic holding member or shell so that there is heat transfer at the point of contact of the members or components.

30 The coil C takes on substantially the position of being at an angle of 45° to the horizontal plane and of being 45° to the vertical plane. The individual loop 10 of each segment of the coil takes on a position of 45° to the vertical plane and 45° to the horizontal plane.

Within the coil is a series of circular loops F 35 wound into the form of a helix in continuation which are a contiguous part of the coil C. The purpose and function of the central loops F is to obtain a complete vaporization of the gases within the central coil. At the inlet end of the coil is an inlet fitting through which the refrigerant liquid enters the coil at a relatively high pressure 40 from an expansion valve (not shown). After the liquid enters the coil through the inlet E, it is vaporized by absorption of heat from the surrounding air which is blown into contact with the coil surface. As the refrigerant passes from one 45 convolution 10 into the next convolution it is more and more vaporized by absorbing heat. The internal loop F serves as an auxiliary vaporizer where all of the liquid which may arrive within 50 the loop is completely vaporized. Hence, com-

plete efficiency of the vaporization of the refrigerant is accomplished within the coil itself.

The coil C is mounted adjacent to the wall of the refrigerator by virtue of a shell, generally designated as G, which shell is a sheet metal plate having flanges 20 and 21, offset from central plate portion 22. The intermediate horizontally positioned connecting portions 24, 26 each have a plurality of port openings 28 therein which communicate with the interior of the refrigerator chamber and through which the air cooled within the shell G is outwardly directed by the operation of the impeller B.

Mounted adjacent the side is the centrifugal blower with an impeller which draws warm air from one portion of the refrigerator and blows the air over the coil C.

The bottom ports force the wall air direct onto the merchandise. Even though the coil of my invention is brought to a temperature of 6° F. no frost is created upon the shield.

The effect of my coil is to reduce the amount of frost which collects on the cooling coil and the relative humidity of the air within the coil is kept high and for any moisture which forms I provide means for carrying it from the interior of the refrigerator so that the goods is not damaged.

The shell G by virtue of its physical contact with the coil is used as a secondary cooling surface. The shell also may be dipped in a tin bath for fusion between the primary (the coil) and the secondary (the shell) surfaces.

It is to be noted that with my construction of the shell and the utilization of the coil its forms a spring contact.

Although my invention has been described in considerable detail, such description is intended as being illustrative rather than limiting, since the invention may be variously embodied, and the scope of the invention is to be determined as claimed.

I claim as my invention:

1. In a refrigerator, the combination of an impeller, a helical coil having spaced convolutions of elliptical form, said impeller being mounted adjacent said coil and being adapted to direct warm air from within said refrigerator upon said coil whereby to effect complete vaporization of a liquid refrigerant flowing through said coil, and a metallic enclosure for said coil, said enclosure having opposite side walls respectively in frictional engagement with correspondingly opposite sides of said coil, and said coil being internally provided with an extension thereof in the form of a helix having a plurality of substantially circular convolutions.

2. In a refrigerator, a coil having a plurality of spaced elliptical convolutions, an impeller to direct warm air from within the refrigerator to and upon said coil, a metallic casing for said coil, said metallic casing having top, bottom and opposite side walls closely embracing said coil, the top and bottom walls of the casing having formed therein a plurality of air discharge ports through which air cooled by said coil is circulated outwardly of the casing by the action of said impeller.

ARNOLD A. D. SHANIS.
